CLAIM

The ornamental design for a seat, as shown and described.

DESCRIPTION

FIG. 1 is a front perspective view of a seat showing our new design in the form of a sofa;

FIG. 2 is a front elevational view thereof;

FIG. 3 is a top plan view thereof;

FIG. 4 is a right side elevational view, the left side being a mirror image thereof;

FIG. 5 is a rear perspective view thereof;

FIG. 6 is a front elevational view of a seat showing our new design in the form of a loveseat; and,

FIG. 7 is a front elevational view of a seat showing our new design in the form of a chair.

The broken lines shown herein are for illustrative purposes only and form no part of the claimed design.

The end views of FIGS. 6 and 7 are like that shown in FIG. 4.

The rear views of FIGS. 6 and 7 are like FIG. 5, the difference being a matter of length.

FIGS. 2 through 7 are shown on a reduced scale with respect to FIG. 1.
